UNITED STATES PATENT OFFICE.

MARTIN L. SNYDER, OF TORRINGTON, WYOMING.

NAIL HOLDING AND DELIVERING DEVICE.

1,170,939.

Specification of Letters Patent.

Patented Feb. 8, 1916.

Application filed June 8, 1915. Serial No. 32,889.

To all whom it may concern:

Be it known that I, MARTIN L. SNYDER, a citizen of the United States of America, residing at Torrington, in the county of 5 Goshen and State of Wyoming, have invented certain new and useful Improvements in Nail Holding and Delivering Devices, of which the following is a specification.

10 The present invention relates to improvements in nail holding and delivering devices, and the invention is designed for the purpose of providing a device to be used by carpenters, mechanics, and others in order 15 that they may have free access to, and be provided with, nails, one at a time so that the nails may be used as desired, and labor and time saved by the operator.

The invention consists in certain novel 20 combinations and arrangements of parts whereby a device of the above character is provided, as will be more fully set forth and specified in the claims.

In the accompanying drawings I have 25 illustrated one complete example, and a modified form of the invention, constructed according to the best modes I have so far devised for the practical application of the principles of the invention, but it will be 30 understood that I may make further changes and alterations if desired, within the scope of my claims, without departing from the spirit of my invention.

Figure 1 is a side elevation of a specially 35 devised trough from which the nails are received, and a portion of the nail magazine is shown in connection with this trough. Fig. 2 is a front elevation of the trough of Fig. 1, on line 2—2, a portion being shown 40 in section. Fig. 3 is a top plan view of a portion of Fig. 1. Fig. 4 is a front elevation of the nozzle portion of the trough of Fig. 1. Fig. 5 is a perspective view of the feeding device. Fig. 6 is a top plan view of a 45 portion of the feeding device, enlarged. Fig. 7 is a fragmentary sectional detail view showing the magazine in position to deliver nails to the feeding device. Fig. 8 is a perspective view showing the magazine 50 and feeding device carried by a belt adapted to be worn by the person using the device.

In the preferred embodiment of my invention, as illustrated in the drawings, I 55 employ a trough or receptacle 1, preferably supported upon legs 2—2, and this trough has inclined side walls 3, which converge at

their lower ends and provide the open bottom or slot 4, which extends the full length of the trough. It will be seen that the rear 60 end of the trough is closed by a wall 5, but the front end is left open, and the side walls converge and project out in front of the trough to form a nozzle 6, which is a continuation of the slotted or open bottom 4. 65 Within the nozzle the side walls thereof are provided with horizontal flanges or ribs as 7—7 which are continued on a line with the edges 8 of the trough.

From this description it will be seen that 70 when nails are dropped indiscriminately into the trough, the shanks of the nails will pass through the slots or open bottom 4, but the larger heads will not pass through this slot, and consequently the nails assume 75 an upright position in the open bottom 4, and the side walls 1^a of the trough guide the shanks of the nails while the edges 8 support the heads of the nails. The edges of the open bottom of the trough are inclined as shown, and it will be seen that the 80 nails will slide down this incline by gravity and pass through the nozzle 6 with the heads of the nails supported on the flanges 7.

In connection with this trough I employ 85 a magazine which is composed of a tube 9, preferably of metal, and provided in its lower edge with a slot 10 which extends throughout the length of the tube. This slot 10 is the same width as the slot 4 in the 90 trough 1, and the magazine tube 9, as shown in Fig. 1, is of a size to fit over the nozzle 6 of the trough. The magazine is adapted to receive nails, while they hang by their heads in a vertical position, from the edge 8 of 95 the trough 1. For this purpose the open end of the magazine 9 is slipped over the end of the nozzle 6, as in Fig. 1. At the end of the magazine 9, a spring detent 11 is provided which overhangs the open end of 100 the magazine, and the lower end of this detent projects in front of the open end of the slot 10, when the spring detent 11 is in normal position. When in this normal position, the spring detent is in position to prevent exit of the nails from the magazine tube, inasmuch as it obstructs the slot 10, and is in the way of any nail heads in the tube. The spring detent carries a finger 12 which projects out in front thereof, and this 110 finger 12 is adapted to engage and ride upon an inclined face 13 of the side walls of the nozzle or spout of the trough 1. Thus, when the tube 9 is applied to the nozzle, the detent

12 is automatically withdrawn from in front of the slot 10, and nails which are supported by their heads within the trough 1 may be transferred by gravity from the trough to 5 the magazine tube. In this manner the magazine tube 9 may be filled with nails which stand upright and are supported within the tube 9 by the heads of the nails which extend over the edges of the slot 10 and support the nails.

In connection with the magazine tube, I employ a feed chute 14, which is made up of two parallel side members 15 which are spaced apart to form a slot 16 which is of a 15 size sufficient to permit the shank of the ordinary wire nail to pass therethrough, but this slot, as is the case with the slot 10 and the slot 4, will not pass the head of the nail, so that the head of the nail is adapted to 20 rest upon the upper edges of the side plates 15. These two plates 15 are held together by brackets 17 and 18, the former also providing a means for grasping the chute, and at one end this bracket 17 is provided with 25 inclined edges 19 which serve a purpose similar to the edges 13 of the nozzle 6. In Fig. 7, the tube 9 is shown delivering nails to the chute, and it will be seen that the finger 12 has ridden up on the inclined surface 30 19 and withdrawn the detent 11 from in front of the slot 10 of the tube 9, so that the nails may slide from the magazine tube 9 into the chute 14. The nails in the chute are supported with their heads resting upon 35 the upper edges of the plates 15, and they are retained in the chute by means of a spring pressed two-armed detent which is pivoted at 20 on the bracket 18. The arm 21 of this detent is provided with a head 22 40 having a cam edge 23, and the arm 24 of this detent is provided with a similar head 25, but in this instance there is no necessity for the use of the cam face. The detent is pivoted at 20 and is adapted to swing horizontally on its pivot. The two heads 22 and 45 25 are located upon a lower plane than the pivot 20, so that they can pass through slots 26 and 27, respectively, located in the plates 15. In Fig. 6 it will clearly be seen that 50 these heads 22, 25 are off-set from each other so that one movement of the detent will permit the ejection from the chute of a nail. A spring 28 is attached at one end to the detent, and at its other end to the diverging 55 wall 29 of the chute.

A second wall 29' forms a guide for the fingers when seeking a nail. Thus, when it is desired to take a nail from the chute, the fingers are inserted between the two guides 29—29' and the spring 28 is pressed upon which moves the detent to the left, as it swings on its pivot 20. The normal position of the spring detent, is shown in

Fig. 5, where the head 25 projects through the slot 27 and closes the open end of the 65 slot 16 and thus holds the nails in the chute. The detent is held in this position by the spring 28. When pressure is applied to the spring and the detent swings on its pivot 20, the head 25 is withdrawn from the nail, 70 and the cam face 23 of the head 22 contacts with the shank of the nail and ejects the nail from the chute into the waiting fingers. As soon as pressure is released from the spring 28, the detent is returned to normal 75 position and the next nail is held at the mouth of the chute 16. Thus, one nail at a time is ejected and furnished, and the operator, after sufficient practice, will become expert in movements and motions 80 necessary to procure the nail from the chute.

In Fig. 8, I have illustrated an adaptation of the device to a belt 30 to be worn upon the body of the wearer and provided with a suspending strap 31. In this instance, the magazine tube 9^a is fastened at 32 to the belt and extends around the belt. The chute 14^a is attached to the magazine 9^a, and the ejecting device is indicated as a whole by the number 33.

From this description, taken in connection with my drawings, it is apparent that I have provided a nail holding and feeding device which is facile and efficient in its operation, which is durable, and which 95 performs the functions of a perfect device in a proficient manner.

What I claim is:—

1. The combination with a nail holding and feeding device having a trough and a 100 nozzle on the trough with a cam edge, of a magazine adapted to receive nails from said trough and provided with a spring detent co-acting with the cam edge, and a chute having a spring pressed detent for 105 ejecting a single nail.

2. In a nail holding and feeding device the combination with a slotted magazine tube having a spring detent overhanging its open end and formed with a finger, of an 110 open bottom gravity feeding nozzle having an upper cam edge for co-action with said finger of the detent as described.

3. The combination with two rigidly spaced slotted plates forming a chute and 115 having outspreading end guide wings, of a spring pressed detent pivoted over the top of said plates and having opposed cam heads adapted to move through the slots in the respective plates, one of said heads 120 being a retaining head and the other an ejecting head, whereby one nail at a time may be ejected from the chute.

In testimony whereof I affix my signature.

MARTIN L. SNYDER.
